UTILITY CABINET FOR SOLID FUEL COOK STOVES

George E. Pickup, Newark, Ohio, assignor to The Florence-Wehrle Stove Co., Newark, Ohio, a corporation of Ohio

Application September 8, 1936, Serial No. 99,710

3 Claims. (Cl. 312—167)

The invention pertains to cabinets for use with cook stoves or ranges of the type having a flat top extending in a single horizontal plane from end to end of the stove.

5 The object of the invention is to increase the utility of such stoves or ranges through the provision of a utility cabinet adapted to utilize to advantage the space at the rear of the range which is occupied in part by the usual flue pipe.

10 The object of the invention thus set forth, together with other and ancillary advantages, is attained by the construction and arrangement shown by way of illustration in the accompanying drawings, in which:

15 Figure 1 is a fragmentary front perspective view of a cook stove range embodying my invention.

Fig. 2 is a similar view with the doors of the cabinet in open position.

20 Fig. 3 is a fragmentary plan section taken approximately in the plane of line 3—3 of Fig. 1.

Figs. 4 and 5 are fragmentary vertical sectional views taken respectively in the planes of lines 4—4 and 5—5 of Fig. 3.

25 My invention is shown as applied to a range having a main or body section with a cooking top 7, a fire box 6 for solid fuel, and one or more additional compartments including an oven 8. At the rear side of the body is a flue connection or 30 elbow 9 projecting some distance from the rear wall of the range and leading upwardly from this elbow is the usual flue pipe 10.

Because of the flue connection and pipe 10 it is necessary when installing the range to position it with its rear wall spaced from the wall of the room. In accordance with the present invention, the space at the rear side of the range may be utilized to advantage through the provision of a utility cabinet rising from the rear edge portion of the top 7 and having laterally spaced sections extended rearwardly on opposite sides of the flue pipe 10 which thus tends to keep the cabinet warm and dry.

35 The utility cabinet provided in accordance with my invention is disposed rearwardly of the range body and projects upwardly from the rear edge thereof a substantial distance. As shown, it provides two compartments 11 and 12 made of substantial depth so as to extend rearwardly on 40 opposite sides of the flue pipe 10, and of substantial height, with the bottom of the compartments 11 and 12 spaced upwardly a substantial distance above the rear edge portion of the stove top 7. The cabinet structure is divided centrally 45 thereof to form the two compartments by means

preferably defining a vertically elongated recess 13 disposed forwardly of the flue pipe 10.

To provide the compartments 11 and 12 and the recess 13, the cabinet structure comprises in the present instance two narrow outer side walls 14 5 suitably supported at their lower ends at the rear edge portion of the stove top. These walls 14 extend upwardly to the top of the structure, which is closed by a top wall 15 substantially wider than said side walls so as to extend rearwardly beyond the side walls. Between the side walls, and in vertically spaced relation to the stove top, is a bottom wall 16 of a width corresponding to the width of the side walls. Extending between the rear edges of said side walls 14 and between the 10 rear edge of the stove top 7 and the rear edge of the bottom wall 16 is a vertical wall plate 17 coextensive with the length of the cabinet. This plate 17 closes the rear end of the space between the rear edge portion of the stove and the bottom 15 wall 16, and also constitutes a forward wall for the lower rear portions of the two compartments 11 and 12 which are closed at their rear sides by a wall member 18.

Said wall member 18 is shaped to provide rear 25 wall portions 19 (Fig. 3), outer side wall portions 20, bottom wall portions 21 (Fig. 5), and inner side wall portions 22 (Fig. 3) joined by a connecting portion 23. As shown, said rear wall member 18 may be formed from a single sheet of 30 metal and suitably secured to the rear edges of the outer side walls 14, the rear edge of the top wall 15 and the rear side of the lower front plate 17 substantially below the rear edge of the bottom wall 16. The inner side wall portions 22 35 and the connecting portion 23 form a channel for receiving the flue pipe 10, the top wall being cut away in its rear central portion above this channel. Said connecting portion 23 is disposed immediately forward of the flue pipe 10 so as to 40 constitute a heat baffle therefor.

To complete the inner sides of the compartments 11 and 12, a pair of narrow plates 25 extend vertically between the top wall 15 and the bottom wall 16, substantially in alignment with 45 the inner side wall portions 22. These inner side plates 25 are thus disposed in laterally spaced relation and cooperate with the connecting wall portion 23 of the rear wall member 18 to form the vertically extending central recess 13 which is 50 closed at its upper end by the top wall 15 and at the lower end by the bottom wall 16. In the present instance, said recess has a semi-circular liner 26 extending from top to bottom of the recess and forming with the inner side plates 25 55

and the connecting portion 23, a dead air space 27.

The compartments 11 and 12 thus formed are closed at their front sides by means of doors 28 hinged at the forward edges of the outer side walls 14 and having their lower edges, like the bottom walls, spaced a sufficient distance above the stove top 7 to clear cooking utensils on the top. Suitable door openings may be defined by a front frame formed by flanges on the forward edges of the outer side walls 14, the top wall 15, bottom wall 16 and inner wall plates 25. Preferably the flange on the top wall extends upwardly and its central portion may be interrupted to receive the casing of an electric lamp 30 of sufficient height to conceal the connection between the upper end of the flue pipe 10 and the pipe (not shown) leading to the stack. Also the flanges on the outer side walls 14 preferably continue downwardly to the stove top for stiffening purposes.

Each of the compartments 11 and 12 may be provided with one or more shelves 31, and similarly the recess 13 may also be equipped with a shelf 32, herein shown substantially circular in form, with the forward portion overhanging the stove top. The compartments are of substantial depth because of the utilization of the space on opposite sides of the flue pipe. Also the rear portions of the compartments formed rearwardly below the bottom wall 16 constitute wells 33 especially adapted to receive pans or plates 34.

It will be seen that through the provision of a cabinet mounted on the range body in the manner set forth, the utility of the range is substantially increased. This is accomplished at a relatively low additional cost of construction and without increasing the space between the range and the wall of the room in which it is installed. As the same time the cabinet is so arranged that the hot gases escaping through the flue pipe 10 serve to keep the compartments 11 and 12 warm and dry.

I claim as my invention:

45 1. For use with a cook stove having a flat top

and a flue pipe extending vertically at the rear of the top, in combination, a cabinet structure adapted to be mounted on the rear edge portion of the top and having a vertical forwardly opening recess disposed to lie forwardly of the flue pipe 5 and two compartments on opposite sides of the recess, doors closing the forward sides of said compartments, said recess having a rear wall portion adjacent the forward side of said flue pipe, and a liner cooperating with said rear wall and the adjacent sides of said compartments to form a dead air space.

2. For use with a cook stove having a flat top and a flue pipe extending vertically at the rear of the top, in combination, a cabinet structure 15 adapted to be mounted on the rear edge portion of the top and having a forwardly opening recess disposed forwardly of the flue pipe and two compartments on opposite sides of the recess, doors closing the forward sides of said compartments, said compartments having forward portions with bottom wall adapted to be in spaced relation upwardly a substantial distance from the stove top, and rear portions with bottom walls in 20 downwardly offset relation to the bottom walls of 25 said forward portions.

3. For use with a cook stove having a flat top and a central flue pipe extending upwardly at the rear edge of the top, in combination, a cabinet structure adapted to be mounted on the rear edge portion of the top and having a horizontal member adapted to be supported in vertically spaced relation to the rear edge portion of the top, an elongated upright plate adapted to extend lengthwise of the top between the rear edge thereof and the rear edge of said horizontal member, and means cooperating with said plate to form compartments adapted to be located on opposite sides of the flue pipe and depending as well substantially below said horizontal member behind said plate to open upwardly behind the rear edge of 30 said horizontal member.

GEORGE E. PICKUP. 45
